LUBRICATING OIL

Joseph Cole, Whiting, Ind., assignor to Sinclair
Refining Company, New York, N. Y., a corpora-
tion of Maine

No Drawing. Application September 23, 1936,
Serial No. 102,167

4 Claims. (Cl. 37—9)

My invention relates to improvements in pour
depressors, compounding agents to be added to
petroleum lubricating oils to lower the tempera-
ture at which such oils cease to flow, and in
methods of making such pour depressors.

5 I produce the pour depressor of this invention
by mixing stearic acid with chlorinated paraffin
wax and treating this mixture with anhydrous
aluminum chloride.

10 Specifically, the pour depressor of this invention
is conveniently produced as follows: A mixture
of 200 parts (by weight) of chlorinated
paraffin wax containing about 43% (by weight)
of chlorine and 100 parts of stearic acid is heated
15 to 120° F. and maintained at that temperature
for 30 minutes. 15 parts of anhydrous aluminum
chloride is added to the resulting mixture, and
the temperature of this mixture is gradually in-
creased, while maintaining thorough stirring,
20 until a temperature of 580° F. is attained. The
mixture may then be filtered while still hot. The
product of this aluminum chloride treatment is
the pour depressor of my invention. It remains
liquid at room temperature.

25 This pour depressor may be compounded with
petroleum lubricating oils in proportions rang-
ing from a fraction of a percent up to several
percent, from 0.1% to 1% or somewhat more
for example. Added to one Pennsylvania lubri-
cating oil originally having a pour test of 25° F.,
30 0.5% (on the oil) of this pour depressor pro-
duced a compounded product having a pour test

of —15° F. Such reductions in the pour test
are attained without impairment of the viscosity
index of the oil, but the compounded products
are usually darker in color than the oil before
addition of the pour depressor.

My invention includes this pour depressor and
petroleum lubricating oils compounded with this
pour depressor as well as the method of mak-
ing the pour depressor. However, I do not now
have any better mode of identification of the 10
pour depressor than the method by which it is
made.

I claim:

1. A method of making a pour depressor com-
prising reacting chlorinated paraffin wax with 15
stearic acid in the presence of anhydrous alu-
minum chloride, and removing the solid con-
stituents from the liquid product of this reaction.

2. A pour depressor which comprises the prod-
uct produced as in claim 1.

3. Compounded petroleum lubricating oils com-
prising the pour depressor produced as in claim 1.

4. The method of depressing the pour point of
a petroleum lubricating oil which comprises re-
acting chlorinated paraffin wax with stearic acid 25
in the presence of anhydrous aluminum chloride,
to form a liquid product, removing solid con-
stituents from this liquid product, and adding
the liquid product to the petroleum lubricating
oil.

JOSEPH COLE.
